UNITED STATES PATENT OFFICE.

CHARLES SPIRO, OF NEW YORK, N. Y., ASSIGNOR TO FEDERAL ADDING MACHINE CORPORATION, OF NEW YORK, N. Y., A CORPORATION OF NEW JERSEY.

CARRIAGE CONTROL MECHANISM.

1,402,265.

Specification of Letters Patent. Patented Jan. 3, 1922.

Application filed April 7, 1920. Serial No. 372,070.

To all whom it may concern:

Be it known that I, CHARLES SPIRO, citizen of the United States, residing at New York, in the county of New York and State 5 of New York, have invented certain new and useful Improvements in Carriage Control Mechanism, of which the following is a specification.

This invention relates to carriage-control 10 mechanism, and particularly to decimal tabulating, margin gage, bell-ringing and line-locking devices adapted to be disposed at the front of a typewriting machine.

The invention has for an object to provide 15 a novel and improved construction of decimal tabulator in which the tabulating stops are mounted upon a carriage to cooperate with a rack thereon and to engage selectively projected abutments disposed upon a 20 support at the front of the typewriter frame and adapted to be actuated by adjacent key devices having lever connections therewith.

A further object of the invention is to present a novel construction of tabulator 25 abutment and actuating key connection therefor which permits the close assemblage of the tabulator disks and the disposition of the key upon the front of the typewriter facing the operator.

Another object of the invention is to provide 30 an improved structure of carriage release comprising a sleeve having an arm disposed to be engaged by a shoulder upon each of the tabulator disks and tensioned to 35 effect the retraction of said disks when pressure is relieved from the key.

Other and further objects and advantages of the invention will be hereinafter set forth and the novel features thereof defined by the 40 appended claims.

In the drawing:

Figure 1 is a front elevation at the rear of the keyboard.

Fig. 2 is a vertical section on line 2—2 of 45 Fig. 1.

Fig. 3 is a similar section on line 3—3 of Fig. 1.

Fig. 4 is an elevation of the control mechanism with the casing removed.

Fig. 5 is a vertical section on line 5—5 of 50 Fig. 3.

Fig. 6 is a detail section on line 6—6 of Fig. 4.

Fig. 7 is an elevation showing the relation 55 of the margin stop and bell and line-lock stop mechanisms.

Fig. 8 is a detail perspective of the tabulator stops.

Fig. 9 is a similar view of the ringing and 60 lock-stop, and

Fig. 10 is a detail section showing the mounting for the margin abutment.

Like numerals refer to like parts in the several figures of the drawings.

The numeral 10 designates the frame of 65 the typewriter, which may be of any desired construction or configuration, and supports the usual carriage 11, provided with the platen 12. At the front of the top plate 13 of the frame a supporting rod 14 is pivotally 70 mounted in posts 15 by any preferred means; for instance, the adjustable screw 16 shown in Fig. 5, by which the bearings for the rod may be properly adjusted to compensate for thrust and to insure proper oscillation thereof. Upon the rod 14, a series 75 of tabulator abutments 17 are mounted in any preferred manner; for instance, the abutment 18 is secured to a sleeve 19, which is rigidly attached by the rod as at 20. Upon 80 this sleeve, the series of abutment disks 17 are mounted to freely oscillate.

The abutment disks 17 and 18 are substantially similar in construction, each being provided with an engaging point 21 85 adapted to be thrown into the path of a stop 22 carried by the carriage and provided upon one face with a restoring shoulder 23 and at its tail portion with a curved socket 24.

This socket receives the curved head 25 90 of the actuating lever 26, mounted to oscillate upon the supporting rod 27, carried by bearings 35 from the frame of the machine. The tails 28 of these levers are deflected laterally as at 29 in Fig. 4, so as to 95 permit a close nesting of the levers adjacent the abutments and the disposition of the tails thereof in a single horizontal plane at separated points to permit the application and attachment of the keys 30. These keys 100 comprise plungers 31, from which curved connectors 32 extend and are provided with pins 33 seated in slots 34 in the tails 28 of the actuating levers. By this arrangement the keys may be disposed in parallel lines 105 as shown in Figs. 1 and 3, and connected to the actuating levers in a single horizontal plane.

For the purpose of restoring the abutments after their actuation, a collar 36 is 110 mounted upon the support 14 and provided with a longitudinally extended bail arm 37,

which rests upon the shoulders 23 of the abutments. This arm is common to all of the abutment members and is held under tension to retain these members in inoperative position by means of a spring 38 extending from a lug 39 upon the collar to a fixed point, such as a post 40 on the shaft 27. When the abutments are thrown into operative position, the bail is placed under tension 10 and the collar rocked to actuate a carriage release mechanism. This may be accomplished through any desired connection, a preferable form thereof being a crank arm 41 upon the collar 36, from which a pending link 42 extends to a lever 43 pivotally mounted at 44 upon a fixed part of the machine and having a pin and slot connection 45 with a bell-crank device 46 pivoted at 47 upon bracket 48. This bell-crank is 15 connected with a member 49 of the carriage escapement mechanism 50, for the release thereof.

The abutment members as just described cooperate with tabulating stops 22 which are 25 slidingly mounted upon a rod 51 carried by the arms 52 of the carriage frame and comprise parallel side walls 53 extended beneath a rack 54 and adapted to engage in the teeth 55 thereof. The stops are normally retained in such engagement by means of a 30 spring 56 secured to the stop and bearing against the rear face of the rack while they may be withdrawn therefrom by a forward movement upon the finger-piece 57 of the stop which places the spring 56 under tension. While both of the walls 53 seat in the rack teeth, only one thereof acts as a 35 contact with the abutments, and the parallel arrangement is designed to give additional resistance to the impact or thrust blow of the tabulating action. The stops are also provided with an indicator finger 58, which cooperates with indications 59 upon the upper face of the rack, which are 40 thus clearly visible to the operator. It will be seen that the construction of the tabulator stop permits its ready adjustment to the desired position upon the rack and its firm connection therewith.

50 The rod or support 14 also carries a collar 60 which forms a unit for the margin abutment, bell-ringing and line-lock connections. The end of this collar next the tabulator abutment 18 is provided with a 55 pivoting slot 61 to receive the pivots 62, of the margin abutment 63, which is of yoke shape to partially embrace the collar, and carries a contact point 64. The margin abutment is also provided with a laterally 60 extending arm 65, which supports a curved spring 66 resting upon the upper face of the collar. As shown in Fig. 3, the margin abutment rests against the tabulating abutment 18, which is provided with an extended web 67 for that purpose, as shown in Fig. 65

3. This abutment being fixed to the shaft, supports the margin abutment in operative position and receives the impact thereof upon contact with the carriage stop 74 in the travel of the carriage toward the right. 70 When it is desired to write within the margin thus established, the margin abutment may be rocked out of the path of the carriage stop by means to be hereinafter described, so that the stop may pass beyond the position of the abutment. When the writing is continued, the margin abutment yields in its contact with the margin stop traveling toward the left and this yielding places the restoring spring under torsional 80 tension, which retracts the abutment to operative position as soon as the carriage stop has passed same.

For the purpose of rocking the margin abutment 63, the collar is provided with a 85 flange 68 having at one face a contact 69 disposed above a margin release lever 70. This lever is substantially similar in construction to the actuating levers 26, and is provided with a collar 71 which carries at 90 its opposite end the deflected arm 72 for connection with the margin release key 73, which is normally disposed at the extreme left of the bank of tabulator keys, but may be otherwise arranged.

95 The collar 60 is also provided with a cam face or flange 75 disposed in a plane to be actuated by a bell and lock stop 76 mounted upon the carriage. This stop is substantially similar in construction to the tabulator stops 22, before described, with the exception that the locking walls 53 thereof are provided with contacts 77 and 78 of different lengths to successively impart different degrees of oscillation to the collar 80 at spaced intervals. While the form of bell and lock stop just described has been found desirable, any construction accomplishing a similar result may be used. At the opposite end of the collar from the flange 75, a 100 bell-ringing connection 79 is secured, and in the present instance comprises a bell hammer 80 adapted to contact with a bell 81 carried by a bracket 82 upon the machine frame in the usual manner. When the 105 flange 75 contacts with the stop 77 the collar is rocked to such an extent as to withdraw the bell hammer to the position indicated by dotted lines in Fig. 2, and as the flange leaves the stop 77, the hammer is restored or thrown into contact with the bell by any desired form of spring, for instance as shown at 83. In the continued movement of the bell and lock stop, the face 78 thereof further depresses the cam flange 120 125 and rocks the bell hammer to a greater extent so as to contact with the face 84 of the rock lever 85 which is pivoted at 86 upon a fixed support 87, and the lower end 88 of this lever carries a pivoted link 89 ex- 130

tending to an arm 90 carried by the axis of a pivoted locking bail 91 which is adapted to be swung beneath the locking face 92 of the key lever 93 mounted in the frame 5 of the machine in the ordinary manner. The locking lever 85 is restored to inoperative position by a tension spring 94, as shown in Fig. 2.

The margin stop 74 is similar in construction to the tabular stops 22, before described, with the exception that a contact lip 95 is provided to engage the face 64 of the margin abutment 63, while the faces 53 of the tabular stops 22 are recessed at 96 to pass the face 64 of the margin abutment. The contact faces of the different stops upon the rack are disposed to traverse parallel horizontal planes and engage only the desired abutment.

20 In order to economize space in the construction of the machine, the carriage control members are disposed at the front immediately adjacent the arc or travel of the type bar, as indicated by the dotted line 25 at 97 in Fig. 2, and these parts are enclosed by a suitable casing or front plate such as 98 having a depending keyboard portion 99 secured to the frame in any desired manner, for instance by means of the screws 100 entering the posts 15. This keyboard portion supports the margin release and tabulating keys in a conveniently accessible bank immediately above the type bar keyboard of the machine.

35 The operation of the invention will be apparent from the foregoing description, from which it will be seen that in the travel of the carriage from left to right the margin stop engages its abutment which is supported by the fixed tabulator abutment and establishes the left margin upon the paper. If it is desired to write within this margin, the margin abutment is rocked out of the path of the stop permitting the same to pass, and in the continued writing this abutment yields under its spring tension to permit the passage of the margin stop in the carriage travel from right to left. The depression of any of the tabulator keys projects the disks 45 into the path of the tabulator stops to perform the usual decimal tabulating functions, and this operation raises the bail from the carriage release collar so as to permit the travel of the carriage to bring the stop thereon into engagement with the projected abutment. As soon as pressure is relieved from the key, the spring from this collar immediately restores the abutment to inoperative position. In the travel of the carriage 50 from right to left, the bell and lock stop engages the flange upon the controlling unit therefor first depressing the same to such an extent as to operate the bell hammer for ringing, while the second spaced face on this stop effects a further depression of the

cam carrying collar to bring the bell hammer into engagement with the line locking lever which throws the locking bail beneath the key levers. If it be desired to release the line lock for further writing at this margin of the paper, a depression of the margin release key rocks the cam face to permit release of the lock stop for that purpose, and the spring upon the lock lever then releases the bail from the key lever, while the actuating collar is restored to normal position through the spring acting upon the bell hammer depending therefrom.

55 It will be seen that the construction presented provides for the assemblage and nesting of all of the carriage controlling members at the front of the typewriter frame and provides a cooperative relation between these members so as to economize in construction and increase the efficiency of operation by the elimination of additional parts. The construction for projecting the tabulator abutment provides for a direct plunger action thereof and a leverage upon these abutments by which they may be 60 thrown into the path of the carriage stops and automatically restored when pressure is removed from the tabulator keys.

65 While the specific construction of this mechanism has been shown and described, 95 still the invention is not confined thereto, as changes and alterations may be made therein without departing from the spirit of the invention.

What I claim is—

1. In a typewriter, a frame, a carriage thereon provided with a rack and tabulating stop at the front thereof, a supporting member at the front of the frame, a series of key controlled decimal tabulator abutments carried by said member to move rearwardly in a vertical plane toward said stop, and a carriage release device mounted upon said member and disposed to be engaged by each of said abutments.

2. In a typewriter, a frame, a carriage thereon provided with a rack and tabulating stop at the front thereof, a supporting member at the front of the frame, a series of key controlled tabulator abutments pivoted upon said member and disposed to act at a letter space distance from each other, and a carriage release device mounted upon the member and disposed to be engaged by each of said abutments.

3. In a typewriter, a frame, a carriage thereon provided with a rack and tabulating stop at the front thereof, a supporting member at the front of the frame, a series of key controlled contacting decimal tabulator abutments pivoted upon said member to swing toward said stop, and a carriage release device mounted upon the member and connected for actuation by direct engagement with said abutments.

4. In a typewriter, a frame, a carriage thereon provided with a rack and depending tabulator stop at the front thereof, a supporting member at the front of the frame, a series of vertically disposed contacting tabulator abutments pivoted upon said member to swing inward toward said stop, a carriage release device mounted upon said member and connected for actuation by each of said abutments, and restoring means from said release device to the frame. 70
5. In a typewriter, a frame, a carriage thereon provided with a tabulating stop, a pivot rod mounted upon the top plate of the frame, a series of vertically disposed tabulator abutments pivoted thereon to swing inward at their upper ends toward said stop, a fulcrum rod mounted forward of and beneath said pivot rod, a series of levers mounted thereon and having direct pivotal contact at their upper ends with the lower ends of said abutments, a face plate, and sliding keys mounted thereon and connected to the lower ends of said levers. 75
6. In a typewriter, a frame, a carriage mounted thereon and provided with a tabulating stop, a rod supported upon the top plate of said frame, a series of vertically disposed abutment disks pivoted upon said rod to swing inward toward said stop, a series of levers pivoted upon the top plate and seated at one end in sockets in said disks, and sliding keys mounted upon the top plate and having lost motion connections with the opposite ends of said levers. 80
7. In a typewriter, a frame, a carriage mounted thereon and provided at its front with a tabulating stop, a supporting member upon the frame disposed longitudinally of said carriage, a series of tabulating abutments pivoted upon said member, the extreme left one of which is secured thereon, keys for actuating said abutments, a sleeve upon said member at the right of said abutments and provided with a restoring spring, an arm upon said sleeve for engaging shoulders upon all of said abutments during their movement into operative position, and an escapement release mechanism connected to 100 said sleeve. 105
8. In a typewriter, a frame, a carriage thereon provided with tabulating stops, a supporting rod upon the frame, a tabulating abutment disk pivoted thereon and provided with a curved actuating seat, a lever fulcrumed upon the frame and provided with a curved head disposed in said seat, and a sliding key plunger located at an angle to said lever and connected directly thereto by a lost motion connection. 110
9. In a typewriter, a frame, a carriage thereon provided with a tabulating stop, a supporting rod upon the frame, a tabulating abutment disk pivoted thereon and provided with a curved actuating seat, a lever ful- 115
- crumed upon the frame and formed with a head disposed in said seat, and a sliding key plunger disposed at an angle to said lever and having a pin and slot connection with the opposite end thereof. 120
10. In a typewriter, a frame, a carriage thereon provided with tabulating stops, a supporting rod upon the frame, a tabulator abutment disk pivoted thereon, an independent key connection pivotally engaging said disk, a carriage release device mounted upon the rod, and an extension therefrom disposed for actuation by means upon said disk. 125
11. In a typewriter, a frame, a carriage thereon provided with tabulating stops, a supporting rod upon the frame, a tabulator abutment disk pivoted thereon, an independent key connection pivotally engaging said disk, a carriage release device mounted upon said rod for actuation by said disk, and means carried by means upon said device for restoring said disk to inoperative position. 130
12. In a typewriter, a frame, a carriage thereon provided with tabulating stops, a supporting rod upon the frame, a tabulator disk pivoted thereon, a key connection for operating said disk, a shoulder upon said disk, a carriage release device pivoted upon said rod and having a bail arm disposed to contact with said shoulder, and means to restore said device. 135
13. In a typewriter, a frame, a carriage thereon provided with tabulating stops, a supporting rod upon the frame, a tabulator disk pivoted thereon, a key connection for operating said disk, a collar mounted upon said rod and provided with a bail arm engaging said disk, a restoring spring between said collar and frame, and an escapement release mechanism connected to said collar. 140
14. In a typewriter, a frame, a carriage thereon provided with tabulating stops, a supporting rod upon the frame, a tabulator disk pivoted thereon and formed with a shoulder, a key connection for operating said disk, a collar pivoted upon said rod and provided with a longitudinal bail extension disposed to be engaged by said shoulder, a crank arm upon said collar, and an escapement release mechanism connected to said arm. 145
15. In a typewriter, a frame, a carriage thereon provided with tabulating stops, a supporting rod upon the frame, a tabulator disk pivoted thereon, a key connection for operating said disk, a collar pivoted upon said rod and provided with a bail arm engaging said disk, a restoring spring between said collar and frame, a crank arm upon said collar, a link depending therefrom, a lever controlled by said link, and an escapement release mechanism connected to said lever. 150
16. In a typewriter, a frame, a carriage thereon provided with tabulating stops, a 155

supporting rod upon the frame, a tabulator disk pivoted thereon, a key connection for operating said disk, a collar pivoted upon the rod and provided with a bail arm engaging said disk, a restoring means between said collar and frame, a crank arm upon said collar, a link depending therefrom, a rock lever having an arm pivoted to said link and an oppositely disposed arm, a vertically disposed crank device having one member pivoted to the last mentioned arm, and an escapement release device connected to the opposite member of said crank device.

17. In a typewriter, a frame, a carriage thereon provided with tabulating stops, a support upon the frame, a series of closely assembled tabulating abutments pivoted thereon, a series of levers pivotally engaging said abutments and having laterally deflected body portions, and sliding keys mounted upon the body portion and pivoted to the deflected ends of said levers.

18. In a typewriter, a frame, a carriage thereon provided with tabulating stops, a support upon the frame, a series of tabulating abutments pivoted thereon, a series of levers pivotally connected to said abutments and having laterally deflected body portions, and sliding keys disposed in parallel rows and having oppositely deflected stems arranged to pivotally engage said levers in a single horizontal plane.

19. In a typewriter, a frame, a carriage thereon provided with tabulating stops, a support upon the frame, a series of tabulating abutments pivoted thereon, a series of levers pivotally connected to said abutments and having laterally deflected substantially parallel body portions, and sliding keys arranged in parallel rows and having curved stems disposed to pivotally engage said levers in a single horizontal plane.

20. In a typewriter, a frame, a carriage thereon provided with tabulating stops, a support upon the frame, a series of tabulating abutments pivoted thereon and provided with retracting shoulders and curved seats, tension controlled means engaging said shoulders, a series of levers having curved heads disposed in the seats of said abutments, and a series of keys mounted upon the frame and having pivotal connection with the tails of said levers.

21. In a typewriter, a frame, a carriage thereon provided with tabulating stops, a support upon the frame, a series of tabulating abutments pivoted thereon and provided with retracting shoulders, a tension controlled collar mounted upon said support and having a bail arm common to all of said shoulders, a series of levers connected to said abutments, and a series of keys mounted upon the frame and connected to said levers.

22. In a typewriter, a frame, a carriage thereon provided with a tabulating stop, a

rod pivotally mounted upon the frame, a tabulating abutment carried by a sleeve secured to said rod, a series of abutment disks loosely mounted upon said sleeve and closely assembled against said tabulating abutment, and means for swinging said abutment and disks.

23. In a typewriter, the combination of a frame, a carriage mounted thereon and provided at its front with a tabulating stop, a series of abutments mounted upon the front of the frame to swing rearwardly in a vertical plane to engage said stop, keys upon the front face of the frame for actuating said abutments, a restoring device disposed at one side of said abutments and having a horizontal member located in the path of travel of each thereof, and an escapement release mechanism connected to said restoring device for operation in one movement thereof.

24. In a typewriter, a frame, a carriage mounted thereon, a stop member upon the carriage, a movable abutment member cooperating therewith, a support upon the frame, a rocking collar upon said support provided with an arm engaging said abutment, restoring means between said collar and frame, a crank arm upon said collar, a carriage release mechanism, and a connection between said crank arm and mechanism.

25. In a typewriter, a frame, a carriage mounted thereon, a stop member upon the carriage, a movable abutment member cooperating therewith, a rocking collar supported upon the frame and provided with an arm engaging said abutment, a restoring spring between said collar and frame, a crank arm upon said collar, a link depending therefrom, a lever having an arm pivoted to said link, a crank device having one member pivoted to said lever, and a carriage release device connected to the opposite member of said crank device.

26. In a typewriter, a frame provided with posts at its front portion, a supporting rod having pivotal bearings in said posts, an abutment member secured to said rod and carrying a series of contacting decimal abutment disks loosely mounted thereon, a front casing enclosing the beforementioned parts, and sliding keys mounted therein and connected for actuating said abutments.

27. In a typewriter, a frame provided with posts at its front portion, a supporting rod mounted therein, abutment members pivoted upon said rod to swing inwardly, a front casing enclosing said members and having a depending key board portion facing the front of the typewriter, and sliding keys mounted in said portion and connected to said abutment members.

In testimony whereof I affix my signature.

CHARLES SPIRO.
